SPRING BALANCED CONTAINER LID

Ray F. Kuns, Madisonville, Ohio

Application March 21, 1932. Serial No. 600,160

12 Claims. (Cl. 220—47)

The invention relates to containers having lids which are hingedly connected with the body and adapted to be manually opened.

Heretofore considerable manual force, as well as inconvenience and energy, has been required to open containers whose lids are pivotally or hingedly connected with the body particularly if the lid is relatively heavy. The bodies utilized on trailers' chassis', and which are intended to contain campers' equipment, and the like, usually are constructed with a lid which, when opened, forms one-half of the floor and walls, of a house or place of habitation which may be utilized for sleeping and cooking. Particularly, because containers of this nature are relatively large and heavy, considerable manual force necessarily is required to open or raise their lids.

Therefore, the general object of the invention is to provide simple, efficient and dependable means adapted automatically to equalize, or compensate, and reduce the manual effort or force ordinarily required to open and close the lid of a container.

Other objects of the invention are to provide simple, efficient and practical means whereby a resilient member, such as a coil spring, is utilized to impart force or power for the purpose of assisting a person to lift said lid when opening and closing said container; and to provide means whereby the tension of said coil spring is adapted to impart force to retain said lid in a stationary position intermediate the open and closed position.

The invention consists in providing resilient means having such connection with the lid of a container that said resilient means is adapted to exert force to raise said lid, and to exert force to sustain said lid while the same is being lowered.

The invention, also, consists in the combination, arrangement and details of the parts and in other features made apparent by reference to the drawings, the hereinafter specification and the claims.

In the drawings:

Fig. 1 is a plan view of the invention in closed position;

Fig. 2 is a side elevational view of the invention shown in closed position;

Fig. 3 is a side elevational view of the invention shown in partly open position, with parts broken away;

Fig. 4 is a side elevational view of the invention shown in fully opened position and with dotted lines showing the lid in partly closed position; and

Fig. 5 is a plan view of the invention shown in wide open position.

In the preferred construction of the invention I provide the container 1 comprising the bottom or body 2 and the top or lid 3. The body comprises the integrally formed ends 4 and 5, sides 6 and 7, and bottom 8 and has the open top 2'. The lid comprises the integrally formed ends 9 and 10, sides 11 and 12, and top 13, and has the open bottom 3'.

The width of the body 2, or the distance between the outer surfaces of the sides 6 and 7, is considerably less than the width of the top 3, or the distance between the inner surfaces of the sides 11 and 12 and the sides 6 and 7, respectively, are offset inwardly from the sides 11 and 12 for purposes hereinafter fully explained.

The end 4 of the body 2 is hingedly connected with the end 10, of the top 3, as by the usual hinge 14 positioned intermediate the upper edge 15 and the bottom 8, of the body 2, the hinge being positioned a slight distance closer to the edge 15 than the distance from the bottom 8.

Positioned adjacent each side 6 and 7, and the outer edges of the bottom 8, of the body 2, are the tubes 16 and 17 secured in fixed relation with respect to the body 2 as by the spaced apart bands 18 received around the tubes. The bands 18 are fixed to the respective sides of the body 2 as by the rivets 19 which are combinedly received through the bands and the respective sides.

Received within the tubes 16 and 17, respectively, are the coil springs 20 and 21 having their rear end 22 secured to the rear end 23 of the tubes, as by the bolts 24 which protrude outwardly through the rear end of the tubes.

Rotatably mounted on the outer surfaces of the sides 6 and 7, and adjacent the lower edges of the sides and adjacent the bottom 8 and the end 4, of the body 2, are the pulleys 25 which are mounted upon the shafts 26 having their inner ends received in the sides 6 and 7 and the pulley plates or supports 27 which are attached to the outer surfaces of the sides. The bolts or rivets 28 fix the plates 27 to the sides of the body 2.

Suitably fixed to the front end 29 of the coil springs 20 and 21 are the cables 29' received around or threaded through the pulleys 25.

Rotatably mounted on the outer surfaces of each side 6 and 7, and adjacent the upper edge 15 and above the end 4, of the body 2, are the horizontally aligned pulleys 30 and 31 whose outer edges may contact, or be slightly spaced apart. The cables 29' are received between, or

threaded through the respective pulleys 30 and 31 which are rotatably mounted upon the shafts 32 and 33 whose inner ends are fixedly mounted in the sides 6 and 7 and in the pulley support plate 34 secured to the sides as by the bolts or rivets 34'. The upper ends 35 of the cables 29' are secured to the studs 36 suitably secured in the sides 11 and 12 of the lid 3. The studs 36 project outwardly of the lid and are advantageously disposed about centrally of the respective sides.

As previously explained, the width of the body 2 is considerably less than the width of the lid 3. Therefore, when the lid is in closed position, as shown in Figs. 1 and 2, the cables 29', pulleys 30 and 31 and pulley 25 are received intermediate the respective sides of the body and the lid.

The mechanical operation of the invention is as follows:

- 20 Assume the lid 3, of the container 1, is closed, telescoping, over the body 2, as shown in Figs. 1 and 2. The operator may project his fingers in contact with the lower edge 37 of the lid 3 which, when the container is closed, is spaced upwardly from the bottom 8, of the body, a sufficient distance to prevent contact of the lower edge 37 of the lid with the tubes 16 and 17. Manual force exerted upwardly, with respect to the lid 3, causes the lid to pivot on the hinge 14.
- 25 Simultaneously, tension of the cables 29' is exerted by the coil springs 20 and 21 since, when the lid 3 is in closed position, as shown in Figs. 1 and 2, the coil springs 20 and 21 are elongated, or in tension. The force exerted by the springs 30 equalizes, compensates or reduces the amount of normal manual force required to open the lid to the position shown in dotted lines in Fig. 4. When the lid is forced further upwardly, near or at a balanced position, the cables 29' are drawn inwardly by the coil springs 20 and 21 which are in neutralized position. Further manual force exerted in the same direction, indicated by the arrow 38, against the lid 3 causes the studs 36 to be removed a farther distance from the pulleys 30 and 31, thereby exerting tension on the cables 29' which extend the coils springs 20 and 21. The force required to extend the springs equalizes or reduces the normal manual upward force required to lift or lower the lid slowly to the open position shown in Figs. 3 and 4. While the lid 3 remains in fully opened position, as shown in Fig. 4, the cables 29' exert force caused by tension of the coil springs 20 and 21, and the springs remain in elongated or extended position while the lid is in fully opened position. However, the normal force exerted by the coil springs 20 and 21 with respect to the cables 29' is not sufficient to overcome the force of gravity which retains the lid 3 in open position.
- 30 When it is desired to close the container 1, as by lifting the end 9 of the lid 3 upwardly, the operator is required only to exert slight manual force since the tension in the coil springs 20 and 21 is transmitted to the cables 29' which in turn exert upward pressure in contact with the studs 36 because the pulleys 30, on which the cables are resting, are positioned above the studs 36 and the pulleys 25 are positioned beneath the pulleys 32 and 33. When the lid 3 is elevated to near or at a balanced position the coil springs 20 and 21 are in normal or neutralized position. Further movement of the lid 3, to the position shown by dotted lines in Fig. 4, causes the cables 29' to move from the pulley 30 and rest upon the pulley 31 thereby causing the cables 29' to elongate the

80 springs 20 and 21. The force exerted by the springs tends to prevent the force of gravity from drawing the lid in its downward position, shown in Figs. 1 and 2, whereby a relative small manual force exerted upwardly, against the edge 37 of the lid, is sufficient to prevent the lid from falling rapidly to closed position.

85 An advantage of the invention is that the coil springs 20 and 21 exert force to assist the operator in lifting the lid 3 from either a closed or open position to a balanced position in which position only slight manual force is required to prevent the lid from falling to closed position or falling to the open position. Irrespective of the direction in which the lid 3 is moved from the balanced position the force exerted by the coil springs 20 and 21 co-operates with the operator in assisting and relieving him from exerting the normal force required to prevent the lid from rapidly falling, by force of gravitation, to the 90 open or closed position.

95 Another advantage of the invention is that the double or twin pulleys are positioned in close relation with each other, whereby the cables 29' are adapted to swing automatically from contact with the pulley 31 into contact with the pulley 30, when the lid is being opened, and when the lid is being closed the cables 29' are adapted to automatically swing from contact with the pulley 30 into contact with the pulley 31.

100 The importance of equalizing the manual force required to lift the lid from the closed position shown in Figs. 1 and 2 to the balanced position, and the upward pressure required to slowly lower the lid from the balanced position to the open 110 position shown in Figs. 4 and 5, is readily appreciated when it is considered that numerous kinds of containers, particularly those such as telescoping bodies utilized on trailers, are sufficiently large to provide ample space for sleeping space and cooking as well as storage for heavy equipment utilized by campers.

115 Still another advantage of the invention is that the normal force exerted by the coil springs 20 and 21 is obtained without expenditure, except 120 cost of installation of the parts as previously explained.

125 It is apparent that I have invented a practical device adapted to considerably relieve an operator from exertion of manual force in opening and closing lids of various kinds of containers. It is, also, readily apparent that the size and strength of the cables 29' and springs 20 and 21 may be calculated in consideration of the weight 130 of the lid 3, whereby under all circumstances only slight manual force is required to open the lid from closed position and to close the lid from open position.

135 While I believe that the form of the invention illustrated in the drawings and referred to in the above description, as the preferred embodiment, is efficient and practicable, yet realizing that the conditions concurrent with the adoption of the device will necessarily vary, I desire to emphasize 140 the fact that changes in the details may be resorted to, when required, without sacrificing any of the advantages of the invention as defined in the claims. Various changes may be made in the general form and arrangement of mechanical 145 parts described without departing from the invention. Hence I do not limit myself to the precise details of the materials or the size and shape thereof as set forth, but consider myself at liberty to make such changes and alterations as fairly 150

fall within the spirit and scope of the appended and final claims.

What I claim as new and desire to secure by Letters Patent is:

- 5 1. A container comprising a body, a lid, a hinge connecting said body with said lid, means fixed to the upper edge and adjacent said end of said body, a spring in tension fixed to the lower edge of said body and in parallel relation therewith, said lid having an inwardly extending means centrally disposed of a side, and below said first mentioned means, a cable connected with an end of said spring adjacent said end of said body and the other end of said cable being connected 10 with said last mentioned means, said cable being threaded through said first mentioned means, said hinge being below an extended portion of a line through said first mentioned means and said second mentioned means and said second mentioned means being below a line extended through said first mentioned means and said hinge whereby said spring exerts force tending to open said lid when said container is closed. 15 2. A container comprising a body, a lid, a hinge connecting one end of said body with said lid, means fixed to said body, a spring in tension fixed to the lower edge of said body, said lid having means, a cable connected with an end of said spring adjacent said end of said body and the other end of said cable being connected with said last mentioned means, said cable being threaded through said first mentioned means, said hinge being below a portion of a line extended through said first mentioned means and said second mentioned means and said second mentioned means being below a portion of a line extended through said first mentioned means and said hinge and said first mentioned means being positioned between said hinge and said second mentioned means whereby said spring exerts force tending to open said lid when said container is closed. 20 3. A container comprising a body, a lid, a hinge connecting said body with said lid, means fixed to said body, a spring in tension fixed to said body, said lid having means, a cable connected with said spring and said last mentioned means, said cable being threaded through said first mentioned means, said first mentioned means being above a line extended through said hinge and said second mentioned means and said first mentioned means being positioned between said hinge and said second mentioned means whereby said spring exerts force tending to open said lid when said container is closed. 25 4. A container comprising a body, a lid, a hinge connecting said body with said lid, means fixed to said body, said lid having an inwardly extending means, a cable connected with said spring and said last mentioned means, said cable being movable on said first mentioned means, said second mentioned means being below a line extended through said hinge and said first mentioned means and said first mentioned means being positioned between said hinge and said second mentioned means whereby said spring exerts force tending to open said lid when said container is closed, and said spring exerts force tending to close said lid when said lid is in open position. 30 5. A container comprising a body, a lid hingedly connected with said body, means fixed to said body, a spring in tension fixed to said body, said lid having means, a cable connected with said spring and said last mentioned means, said cable being threaded through said first mentioned means, said second mentioned means being below a line extending through said first mentioned means and said hinge and said first mentioned means being positioned between said hinge and said second mentioned means whereby said spring exerts force tending to open said lid when said lid is in open position, said second mentioned means being below a line extending through said first mentioned means and the hinged connection of said lid with said body and said first mentioned means being positioned between said second mentioned means and said hinged connection whereby said spring exerts force tending to open said lid when said container is closed, and said spring exerts force tending to close said lid when said lid is in open position. 35 6. The combination with a container having a body and a lid hingedly connected therewith, of resilient means connected with said body, a cable connected with said resilient means and to said lid, and means comprising a pulley on said body through which said cable is threaded and said pulley, cable, resilient means and said connection of said cable with said lid being so positioned that said resilient means is adapted to exert force tending to raise said lid from a closed position, and said resilient means is adapted to exert force tending to raise said lid from an opened position. 40 7. The combination with a container having a body and a lid connected therewith, of means connected with said body, a cable connected with said means and to said lid, and means comprising a pulley on said body through which said cable is threaded and said pulley, cable, said first mentioned means and said connection of said cable with said lid being so positioned whereby said first mentioned means is adapted to exert force tending to raise said lid from a closed position, and said first mentioned means is adapted to exert force tending to raise said lid from an opened position. 45 8. In a container, a body, a lid having an end hingedly connected with an end of said body, said hinge being positioned intermediate the top and bottom of said body, a horizontal coil spring fixed to the lower edge of a side of said body and extending parallel with said edge, a pulley fixed to said lower edge and adjacent said end of said body, a pair of horizontally aligned pulleys fixed to said body adjacent its upper edge and adjacent said end of said body, said lid having a side off set from said side of said body, said lid side having a lug therein substantially centrally disposed of said side a cable having an end fixed to an end of said spring and threaded through said first mentioned pulley and between said pair of pulleys and having its other end fixed to said lug, said spring being in tension when said lid is in fully open and in closed position, said lug being below a line extended through said pair of pulleys and the hinged connection of said body with said lid whereby said spring exerts force, through said cable, tending to close said lid from its fully open position and tending to open said lid from its closed position. 50 9. In a container, a body, a lid, a hinge connecting said body with said lid, a horizontal coil spring fixed to the lower edge of a side of said body and extending parallel with said edge, a pulley fixed to said lower edge and adjacent said end of said body, means fixed to said body adjacent its upper edge and adjacent said end of said body, said lid having a side off set from said side of said body, said lid side having a lug there-in substantially centrally disposed of said side, a cable having an end fixed to said spring and threaded through said pulley and said means and having its other end fixed to said lug, said spring being in tension when said lid is in fully open and in closed position, said lug being below a line extended through said first mentioned pulley and the hinged connection of said body with said lid whereby said spring exerts force, through said cable, tending to close said lid from its fully open position and tending to open said lid from its closed position. 55 10. In a container, a body, a lid, a hinge connecting said body with said lid, a horizontal coil spring fixed to the lower edge of a side of said body and extending parallel with said edge, a pulley fixed to said lower edge and adjacent said end of said body, means fixed to said body adjacent its upper edge and adjacent said end of said body, said lid having a side off set from said side of said body, said lid side having a lug there-in substantially centrally disposed of said side, a cable having an end fixed to said spring and threaded through said pulley and said means and having its other end fixed to said lug, said spring being in tension when said lid is in fully open and in closed position, said lug being below a line extended through said first mentioned pulley and the hinged connection of said body with said lid whereby said spring exerts force, through said cable, tending to close said lid from its fully open position and tending to open said lid from its closed position. 60 11. In a container, a body, a lid, a hinge connecting said body with said lid, a horizontal coil spring fixed to the lower edge of a side of said body and extending parallel with said edge, a pulley fixed to said lower edge and adjacent said end of said body, means fixed to said body adjacent its upper edge and adjacent said end of said body, said lid having a side off set from said side of said body, said lid side having a lug there-in substantially centrally disposed of said side, a cable having an end fixed to said spring and threaded through said pulley and said means and having its other end fixed to said lug, said spring being in tension when said lid is in fully open and in closed position, said lug being below a line extended through said first mentioned pulley and the hinged connection of said body with said lid whereby said spring exerts force, through said cable, tending to close said lid from its fully open position and tending to open said lid from its closed position. 65 12. In a container, a body, a lid, a hinge connecting said body with said lid, a horizontal coil spring fixed to the lower edge of a side of said body and extending parallel with said edge, a pulley fixed to said lower edge and adjacent said end of said body, means fixed to said body adjacent its upper edge and adjacent said end of said body, said lid having a side off set from said side of said body, said lid side having a lug there-in substantially centrally disposed of said side, a cable having an end fixed to said spring and threaded through said pulley and said means and having its other end fixed to said lug, said spring being in tension when said lid is in fully open and in closed position, said lug being below a line extended through said first mentioned pulley and the hinged connection of said body with said lid whereby said spring exerts force, through said cable, tending to close said lid from its fully open position and tending to open said lid from its closed position. 70 13. In a container, a body, a lid, a hinge connecting said body with said lid, a horizontal coil spring fixed to the lower edge of a side of said body and extending parallel with said edge, a pulley fixed to said lower edge and adjacent said end of said body, means fixed to said body adjacent its upper edge and adjacent said end of said body, said lid having a side off set from said side of said body, said lid side having a lug there-in substantially centrally disposed of said side, a cable having an end fixed to said spring and threaded through said pulley and said means and having its other end fixed to said lug, said spring being in tension when said lid is in fully open and in closed position, said lug being below a line extended through said first mentioned pulley and the hinged connection of said body with said lid whereby said spring exerts force, through said cable, tending to close said lid from its fully open position and tending to open said lid from its closed position. 75

a line extended through said hinge and said means when said lid is closed whereby said spring exerts force, through said cable, tending to close said lid from its fully open position and tending to open said lid from its closed position.

10. In a container, a body, a lid hingedly connected with an end of said body, a coil spring fixed to the edge of a side of said body, a pulley fixed to said edge and adjacent said end of said body, a pair of pulleys fixed to said body adjacent its upper edge and adjacent said end of said body, said lid having a side offset from said side of said body, said lid side having a lug therein, a cable having an end fixed to said spring and threaded through said first mentioned pulley and between said pair of pulleys and having its other end fixed to said lug, said spring being in tension when said lid is in open and in closed position, and said lug being below a line extended between said pair of pulleys and through the hinge connected of said lid with said body, and said first mentioned means being positioned between said second mentioned means and said hinged connection whereby said spring exerts force, through said cable, tending to close said lid from its open position and tending to open said lid from its closed position.

11. A container comprising a body, a lid, a hinge connecting said body with said lid, means fixed to the upper edge and adjacent said end of said body, a housed spring in tension fixed to the lower edge of said body, and in parallel rela-

tion therewith, means attached to lower edge of said body, said lid having an inwardly projecting means centrally disposed of a side and below said first mentioned means, a cable having one end connected with said housed spring adjacent said end of said body and the other end of said cable being connected with said third mentioned means, said cable being threaded through said first mentioned means and through said second mentioned means, said hinge being below an extended portion of a line through said first mentioned means and said third mentioned means, whereby said spring exerts force tending to open said lid when said container is closed.

12. A container comprising a body, a lid, a hinge connecting said body with said lid, means fixed to the upper edge and adjacent said end of said body, a spring in tension fixed to the lower edge of said body, means attached to lower edge of said body, said lid having an inwardly projecting means, a cable having one end connected with said spring and the other end of said cable being connected with said third mentioned means, said cable being threaded through said first mentioned means and through said second mentioned means, said hinge being below an extended portion of a line through said first mentioned means and said third mentioned means, whereby said spring exerts force tending to open said lid when said container is closed.
